DESIGN FOR A TRANSPARENT FOOD RECEPTACLE

Herbert V. Sharlitt and Philip J. Arnoff,
Cleveland, Ohio

Application October 25, 1938, Serial No. 80,665

Term of patent 3½ years

To all whom it may concern:

Be it known that we, Herbert V. Sharlitt and Philip J. Arnoff, citizens of the United States, residing at Cleveland, Cuyahoga County, Ohio, have invented a new, original, and ornamental Design for a Transparent Food Receptacle, of which the following is a specification, reference being had to the accompanying drawing, forming part thereof, and in which:

Figure 1 is a perspective view of the transparent food receptacle showing our new design, while Figure 2 is a diametrical vertical sectional view through the same.

We claim:

The ornamental design for a transparent food receptacle, substantially as shown.

HERBERT V. SHARLITT.
PHILIP J. ARNOFF.
